UNITED STATES PATENT OFFICE.

ARTHUR J. DUPONT, OF ADAMS, MASSACHUSETTS.

FLASH-LIGHT.

1,132,173.

Specification of Letters Patent. Patented Mar. 16, 1915.

Application filed March 19, 1914. Serial No. 825,812.

To all whom it may concern:

Be it known that I, ARTHUR J. DUPONT, a citizen of the United States of America, residing at Adams, in the county of Berkshire and State of Massachusetts, have invented a new and useful Flash-Light, of which the following is a specification.

My invention relates to improvements in electric illuminating devices or lamps known as "flash-lights", and more especially to improvements in the flash-light covered by United States Letters Patent, No. 1,074,354, such improvements residing particularly in means whereby a battery of ordinary form can be utilized, and in certain peculiar switch members. These, together with other features, all as hereinafter set forth, constitute the present invention.

The objects of my invention are, first, to provide a flash-light case which is capable of receiving an ordinary stock battery, and at the same time is adapted to the hand; second, to furnish means whereby such a battery is made available for my purpose without changing the construction of or mutilating the terminals with which said battery is originally furnished; third, to afford convenient means for preventing accidental closing of the circuit to either lamp, as for example when the device is carried in the pocket, and the consequent waste of battery energy and needless activity of the lamps, and, fourth, to provide a convenient switch for one of the lamps, in addition to the finger switch therefor, by means of which additional switch the lamp controlled thereby can be illuminated for a prolonged or an indefinite period, without the aid of the finger that is usually employed to produce such illumination.

No wires whatever are employed in this construction, which is an important and valuable feature, owing to the work, trouble and expense involved in wiring devices of this kind and keeping them in repair.

Other objects and advantages will appear in the course of the following description.

I attain the objects and secure the advantages of my invention by the means illustrated in the accompanying drawings, in which—

Figure 1 is a back side or rear elevation of a flash-light which embodies a practical form of my invention; Fig. 2, a front side or front elevation of said flash-light; Fig. 3, an approximately central vertical section

through the case, looking toward the front side; Fig. 4, an enlarged top plan or front end elevation of the interior parts as they would appear if the case at that end were cut away, the end lamp being represented by two dotted circles, since such lamp would be removed with such case end; Fig. 5, an enlarged fragmentary detail, in section, showing the auxiliary switch for the end lamp; Fig. 6, an enlarged bottom plan or inside view of said auxiliary terminal, and, Fig. 7, an enlarged back side elevation of the battery with the regular and auxiliary terminals or circuit-forming contact members.

Similar numerals refer to similar parts throughout the several views.

Referring to the drawings, it will be seen that a case 1 is provided for the reception of an ordinary dry battery 2, such case having a concave front side 3 to fit the back of the hand, but otherwise having generally plain sides. By thus constructing the case 1 a special battery is not required, and said case is as adaptable to the hand as when the same is made concavo-convex. The case 1 is provided with perforated lugs 4—4 on the side edges for a strap or band with which to attach said case to the hand, and said case is further provided with a bottom or rear-end cover 5. The cover 5 has its back side or edge hinged at 6 to the corresponding side of the case 1 at the bottom or rear end, and has a front lug 7 to snap into engagement with a protuberance 8 on the front side of said case near the bottom or rear end of the same.

The battery 2, which has the usual pole pieces or terminals 9 and 10, is adapted to fit snugly within the case 1, without encroaching upon the little space required for the action of the several interior switch members, or that occupied by the interior portions of two electric lamps 11 and 12, said battery being held transversely between the straight and concave sides and the straight edges of said case, and longitudinally between the cover 5 and the parts with which the battery terminals contact.

The battery 2 or its terminal 10 is provided with a removable auxiliary terminal 13, which is required in this device in order to enable a common form of battery to be used, and which is removed from one battery to another whenever a change is made or a new battery substituted for an old one.

The terminal 13 is merely a strip of metal having a pair of ears or lugs 14 at one end, and being provided with a set-screw 15. The terminal 13 is placed in position and secured 5 by slipping it onto the terminal 10 at the free end of the latter, with the lugs 14 under said terminal 10, moving said terminal 13 along toward the attached end of said terminal 10 as far as possible, and then 10 tightening the set-screw 15 onto said terminal 10. The set-screw 15 is tapped into the terminal 13 and passes through to engage that part of the terminal 10 which is in the grasp of the lugs 14. The terminal 13 is so 15 bent that its free end stands clear of the terminal 10. The auxiliary terminal is released and removed from the terminal 10 by simply loosening the set-screw 15 and withdrawing said auxiliary terminal.

20 The lamp 11 is set in the upper or front end of the case 1, and over this is a bull's-eye 16, while the lamp 12 is set in the back of said case near the aforesaid end and behind a bull's-eye 17. These lamps are of 25 ordinary construction and similar to each other. The bull's-eyes 16 and 17 are similar to each other except in color, the bull's-eye 17 being preferably red, and the bull's-eye 16 preferably clear or without color. The 30 lamp 11 is for ordinary or general use and may be termed the observation lamp, while the other lamp is designed for signaling and may be termed the signal lamp.

Fastened at 18 to the front side 3 of the 35 case 1 are two switch levers 19 and 20. Each of said levers is offset forwardly, as best shown at 21 in Figs. 2 and 4, and this offset part passes out of the case 1 through an opening 22 in the front 3 just within the 40 upper or front end of said case. The free terminals of the levers 19 and 20 are in the form of T's, as represented at 23. By thus extending and forwardly offsetting the free ends of the levers 19 and 20, they are presented to better advantage for operation by 45 the fingers. These switch levers are made of resilient metal which is a good conductor of electricity, as are the other circuit-forming or contacting members employed in this 50 flash-light. The interior portions of the levers 19 and 20 normally bear against the inner face of the front side 3, but may be actuated rearwardly or inwardly except at the 55 points 18 where they are fastened to said side.

The switch lever 19 has a contact finger 24 that extends therefrom into the vicinity of the case terminal of the lamp 11 and is capable of contacting therewith when said 60 lever is pressed rearwardly or inwardly, normally, however, said finger is out of contact with said case terminal, owing to the arrangement and resilient nature of said lever. The switch lever 20 has a contact finger 25 which extends therefrom into the

vicinity of the terminal 26 of the lamp 12 and is capable of contacting therewith when said lever is pressed inwardly, but normally said finger is out of such contact, as is the case with the finger 24 relative to the case 70 terminal of the lamp 11.

Fastened at 27 against the inside of the back of the case 1 is a spring switch 28, which normally lies against said back, for approximately the entire length of said 75 switch, and causes a button 29 carried thereby and operating through an opening 30 in said back to protrude from said opening outside of the case. At the base of the switch 28 is a finger 31 that is within contacting 80 distance of the case terminal of the lamp 11. A slide 32 is arranged in guides 33 on the outside of the case adjacent to the button 29, and the latter is actuated inwardly, to cause the switch 28 to contact through the medium of the finger 31 with the case terminal of the lamp 11, and retained in that position, by pushing the slide 32 upwardly or forwardly in the guides 33 over the protruding end of said button. Upon retracting the 90 slide 32 to free the button 29, the contact made by the switch 28 with the lamp 11 is immediately broken, owing to the resiliency of said switch. This is the auxiliary switch for the observation lamp, and is used when 95 it is desired to have said lamp burn continuously, and to leave free the finger or fingers that otherwise would have to be employed to keep the lamp burning through the medium of the switch lever 19.

100

A safety or master switch is provided to conserve the energy of the battery and lamps, as hereinbefore noted, such switch appearing at 34 and being fastened at 35 to the inside of the edge of the case 1 adjacent 105 to which the lamp 12 is located. Like the auxiliary switch 28, the switch 34 is resilient, and has a button 36 that operates in an opening 37 in the adjacent edge of the case, and protrudes from said opening on 110 the outside of said case. A slide 38 in guides 39 is provided for the button 36, such slide being similar to the slide 32 and functioning in the same manner.

115

When the battery 2 is inserted in the case 1, care must be exercised that the terminal 9 comes adjacent to the switch 34, but said terminal will not then contact with said switch unless the slide 38 be pushed over the button 36, or said button and switch 120 be forced inwardly by some other means. When the battery is in place, the terminal 10 contacts with the case terminal of the lamp 12, and the terminal 13 contacts with the terminal 40 of the lamp 11.

125

To operate the flash-light, it is always necessary first to close the master switch 34, by forcing the slide 38 over the outer end of the button 36, which action causes the bottom part of said switch to bear hard 130

against the battery terminal 9. With the switch 34 closed, the lamp 11 is lighted either by pressing inwardly the switch lever 19, or by closing the switch 28. The switch 28 is closed by forcing the slide 32 over the outer end of the button 29, which action causes the finger 31 at the bottom of said switch to bear hard against the case terminal of the lamp 11. When the switch lever 19 is pressed inwardly, the finger 24 is forced into contact with the case terminal of the lamp 11, and the now complete circuit is through the battery terminals 9 and 13, the switches 28 and 19, the case 1, and the lamp-case terminal and the terminal 40. When the switch 28 is closed, the circuit thus completed is through the same members as before, except that said switch takes the place of the lever 19. The instant either the lever 19 or the switch 28 is released, the latter by withdrawing the slide 32 from the button 31, the light in the lamp 11 is extinguished. If desired, the lamp 11 may be left burning while the lamp 12 is lighted. The lamp 12 is lighted, provided the master switch 34 be still closed, by pressing the switch lever 20, to force its finger 25 into contact with the lamp terminal 26, and said lamp is extinguished as soon as said lever is released. The circuit closed by the lever 20, when pressed inwardly, is made up of the battery terminals 9 and 10, the switches 34 and 20, the case 1, and the case terminal of the lamp 12 and the terminal 26, this and the other circuits being, of course, from and to the battery 2. When through using the flash-light, both lamps should be cut out by releasing the button 36 from the slide 28, and thus breaking the contact between the switch 34 and the terminal 9, and entirely disconnecting from the case 1 one pole of the battery 2. No circuits can be completed while one pole of the battery is disconnected. The reason for disconnecting the battery when the device is not in use has already been given. The flash-light is worn on the hand and operated, through the medium of the switch levers, by the fingers, in the same manner as is fully explained in the hereinbefore referred to patent. Both lamps may be lighted at the same time by means of the levers 19 and 20.

More or less change in the shape, size, arrangement, and construction of the flash-light and its parts may be made without departing from the nature of my invention.

What I claim as my invention, and desire to secure by Letters Patent, is—

1. As an improved article of manufacture, a flash-light attachable to the back of the hand, and comprising a case having a concave front and a flat back, and provided with illuminating means, switch members in said case, and a parallel-sided battery in said case.

2. As an improved article of manufacture, a flash-light attachable to the back of the hand, and comprising a case provided with a lamp, and further provided with a switch member for such lamp, such switch member extending out of the case and having a substantially flat finger-engaging part at its free end, and being, furthermore, offset forwardly to bring said part into operative position behind the fingers of such hand when the device is in place.

3. As an improved article of manufacture, a flash-light attachable to the back of the hand, and comprising a case provided with a lamp, and further provided with a switch member for such lamp, such switch member being in the form of a T at its outer end, whereby such end may be engaged by two or more fingers.

4. As an improved article of manufacture, a flash-light attachable to the back of the hand, and comprising a case provided with a plurality of lamps, and further provided with switch members, such switch members being forwardly offset and substantially flat T-shaped at their outer terminals, whereby each of such terminals is capable of being engaged by two or more fingers.

5. The combination, in a flash-light, with a case provided with a plurality of lamps, of a battery having three terminal pieces, two of which form one pole contacting with said lamps, switch levers for said lamps, and a switch arranged to make and break contact with the battery terminal piece from the other pole.

6. The combination, in a flash-light, with a case provided with a plurality of lamps, of a battery having three terminal pieces, two of which from one pole contacting with said lamps, switch levers for said lamps, and circuit-forming means, independent of said switch levers, between said case and the battery terminal piece from the other pole, one of said first-mentioned terminal pieces and one of said switch levers contacting respectively with the peripheral terminal and the central terminal of one lamp, and the other of said first-mentioned terminal pieces and the other of said levers contacting respectively with the central terminal and the peripheral terminal of the other lamp.

7. The combination, in a flash-light, with a case provided with illuminating means, of a battery having three terminal pieces, one of such terminal pieces being detachable, and circuit-forming and switch members between said battery and said illuminating means and for the control of the latter.

8. The combination, in a flash-light, with a case provided with illuminating means, of a battery having two fixed terminal pieces, a third terminal piece attachable to and detachable from one of said fixed terminal pieces, and circuit-forming and switch mem-

bers between said battery and said illuminating means and for the control of the latter.

9. The combination, in a flash-light, of a case adapted to be attached to the back of the hand, and provided with a lamp, a battery in such case, circuit-forming members between said battery and said lamp, a switch for opening and closing the circuit, such switch having a part that extends into operative position behind a finger of such hand, when the device is in place, and a second switch for opening and closing said circuit.
10. The combination, in a flash-light, of a case adapted to be attached to the back

of the hand; and provided with a pair of lamps, a battery in such case, circuit-forming members between said battery and said lamps, a master switch in said circuit, switches in said circuits for said lamps, said last-mentioned switches having parts that extend into operative position behind the fingers of said hand, when the device is in place, and an auxiliary switch in said circuit for one of said lamps.
